UNITED STATES PATENT OFFICE

ALBERT E. SEHLBACH, OF CHICAGO, ILLINOIS, ASSIGNOR TO ALBERT PICK-BARTH COMPANY, INC., OF CHICAGO, ILLINOIS, A CORPORATION OF NEW YORK

DESIGN FOR A DRINKING GLASS

Application filed May 2, 1932. Serial No. 43,687. Term of patent 7 years.

To all whom it may concern:

Be it known that I, ALBERT E. SEHLBACH, is a citizen of the United States, residing at Chicago, in the county of Cook and State of Illinois, have invented a new, original, and ornamental Design for Drinking Glasses, of which the following is a specification, reference being had to the accompanying drawing, forming a part thereof:

The figure which constitutes the drawing is a perspective view of a drinking glass embodying my new design.

The ornamentation exhibited in the drawing extends completely around the glass.

I claim:

The ornamental design for a drinking glass, substantially as shown and described.

ALBERT E. SEHLBACH.
